Attorney.

UNITED STATES PATENT OFFICE

2,224,206

WATER LEVEL INDICATOR FOR ELECTRICALLY HEATED STEAM IRON

Edward J. Wiggins, Chicago, Ill., assignor to Jack Galter, Chicago, Ill.

Original application December 13, 1939, Serial No. 308,893. Divided and this application February 12, 1940, Serial No. 318,564

1 Claim. (Cl. 73—306)

This is a divisional application from the original Serial No. 308,893 filed December 13, 1939, now Patent 2,190,904 issued February 20, 1940, by the United States Patent Office, for Electrically 5 heated steam iron.

This invention relates to an indicator visible at the exterior of an electrically heated steam iron so that the amount of water in the iron may be determined at any time during its use without 10 interrupting the operation of the same.

Among the objects of this invention is to provide a simple yet accurate means for indicating from the exterior of the iron the level of the water contained therein, so as to prevent unexpected scorching from a dry iron. My invention also contemplates such other objects, advantages and capabilities as will later more fully appear and which are inherently possessed by my 15 invention.

20 While I have shown in the accompanying drawing a preferred form of my invention, yet I wish it understood that the same is susceptible of modification and change without departing from the spirit of my invention.

25 Referring to the drawing, Fig. 1 is a sectional view of a steam iron with my water level indicator; Fig. 2 is a rear elevational view, and Fig. 3 is a top plan view with the handle plate removed.

30 In the embodiment selected to illustrate my invention I disclose an electrically heated steam iron with a shoe plate 10 having a smooth outer bottom ironing or pressing surface 11 and a body member 12 attached to said shoe plate 10. Between said shoe plate 10 and body member 12 is 35 an electrical element 15.

The body member 12 is hollow so as to provide a water chamber 17. Within the water chamber 17 is a steam chamber 18. A steam delivery tube 40 37 passes from the steam chamber 18 downwardly to a plurality of steam openings 40 in the shoe plate 10.

An opening 47 is provided in the top of the body portion 12 within which water may be poured for the water chamber 17. This opening is protected by a removable thumb nut type of screw 48.

At the rear of the iron, electrical plugs 49 communicating with the electrical element 15 in the

iron are provided for contact with an electrical source of supply.

The outer top 22 of the body member 12 has a recess 23 with an indented flange 24 to receive the handle plate 25. Screws 26 attach the handle 5 plate 25 to the flange 24. A handle 27 is attached to the handle plate 25.

Attached to the bottom of the handle plate 25 is a cradle 41 having a bar 42 rotatably attached thereto. Attached to said bar 42 is a rod 50 10 having on its inner end a nonabsorbable float 43 and on its outer end an indicator 44. The float 43 extends into the water chamber 17 through recess 23 and floats on the water. The indicator 44 is visible through window 46 in the handle 15 plate 25 so that the level of the water may be determined from the exterior of the iron. In this way there is no need to iron until the iron is dry—the objects ironed being scorched and the iron impaired. The indicator easily and 20 readily seen warns the user in advance of trouble.

Having thus described my invention, I claim:

In combination with an electrically heated steam iron having a hollow body member providing a water chamber, said body member having 25 removably covered entrance means for the reception of water for the water chamber, a handle plate removably attached to the top of said body member, a handle attached to the top of said handle plate, a water level indicator comprising a 30 cradle attached to the bottom of said handle plate, a bar rotatably attached to said cradle, a rod attached to said bar, a nonabsorbable float attached to the lower end of said rod and adapted to float on the water in the water chamber, an 35 indicator attached to the upper end of said rod, a transparent window positioned in said handle plate, said rod so positioned that said indicator is always visible from the exterior of the iron through said window, said float adapted to be 40 moved to positions determined by the level of the water in the water chamber and in turn to move said indicator before said window in said handle plate to indicate the level of water in the water 45 chamber, said water level indicator removable from the iron upon removal therefrom of the handle plate.

EDWARD J. WIGGINS.
